[57] ABSTRACT

A keyboard musical instrument is fabricated on the basis of an upright piano, and an electronic sound generating system is incorporated therein so as to selectively generate an acoustic piano sound and an electronic sound; a plurality of leaf spring members are provided for the keys of the acoustic piano for imparting a key touch like an electronic keyboard, and a change-over mechanism selectively engages key action mechanisms with the keys and the leaf spring members with the keys so that a player can select the piano key touch or the other key touch like the electronic keyboard depending upon the sound for a performance.

**KEYBOARD MUSICAL INSTRUMENT
HAVING KEY-TOUCH GENERATOR
CHANGING LOAD EXERTED ON KEYS
DEPENDING UPON SOUNDS TO BE
PRODUCED**

FIELD OF THE INVENTION

This invention relates to a keyboard musical instrument and, more particularly, to a keyboard musical instrument having a key-touch generator for changing load exerted to keys.

DESCRIPTION OF THE RELATED ART

Manufacturers presently offer various kinds of keyboard musical instruments such as an acoustic piano, an electronic keyboard, a silent piano and so on, and musicians enjoys these keyboard musical instruments.

The electronic keyboard has a plurality of turnable keys urged to respective rest positions by means of spring members, and sensors monitor the keys to see whether or not a player depresses them. When a musician depresses a key, the key is moved from the rest position toward the end position against the resilient force of the spring member, and the associated key sensor produces a key position signal representative of the downward motion of the key. The key position signal is supplied to a digital signal processor, and a music data code is formed on the basis of the key position signal. The music data code is supplied from the digital signal processor to a tone generator, and the tone generator tailors an audio signal. The audio signal is supplied to a speaker system, and the speaker system produces an electronic sound from the audio signal. The resilient force is simply exerted on the key moved between the rest position and the end position, and the player feels the load constant.

The acoustic piano also has a keyboard consisting of black keys and white keys, and the black/white keys are linked with key action mechanisms for driving hammers. When a players depresses a black/white key, the depressed key actuates the associated key action mechanism on the way from the rest position toward the end position. The key action mechanism rotates the hammer toward a set of strings, and the hammer suddenly escapes from the key action mechanism on the way toward the set of strings. For this reason, the player firstly feels the key heavy, and then feels the key suddenly become light.

The silent piano is a combination of the acoustic piano and the electronic keyboard, and is fabricated on the basis of the acoustic piano. A hammer stopper is provided between the hammers and the sets of strings, and key sensors, a digital signal processor and a tone generator are installed in the acoustic piano. The hammer stopper is changed between a free position and a blocking position. While the hammer stopper is staying in the free position, the hammer can strike the sets of strings, and the silent piano behaves as similar to the acoustic piano. However, when the hammer stopper is changed to the blocking position, the hammers rebound on the hammer stopper after the escape, and do not strike the sets of strings. The key sensors monitor the black/white keys, and supply the key position signal to the digital signal processor. A music data code is formed on the basis of the key position signal, and the tone generator tailors an analog signal so as to produce an electronic sound. The player feels the key touch identical with that of the acoustic piano.

If a musician has played the acoustic piano, he does not feel the key touch of the silent piano strange. However, if he has played the electronic keyboard, he feels the key touch of

the silent piano strange, and yearns to play the silent piano in key touch like the electronic keyboard.

SUMMARY OF THE INVENTION

5 It is therefore an important object of the present invention to provide a keyboard musical instrument in which a key touch is changeable.

In accordance with the present invention, there is provided a keyboard musical instrument comprising: a keyboard having a plurality of keys tunable between rest positions and end positions; a sound generating system responsive to a motion of each of the plurality of keys so as to generate a sound; a key touch generator connected to the plurality of keys, and providing a first resistance to the motion of each of the plurality of keys; a second key touch generator connected to the plurality of keys, and providing a second resistance different from the first resistance to the motion of each of the plurality of keys; and a change-over unit connected to the first key touch generator and the second key touch generator, and selectively enabling the first key touch generator and the second key touch generator.

BRIEF DESCRIPTION OF THE DRAWINGS

25 The features and advantages of the keyboard musical instrument according to the present invention will be more clearly understood from the following description taken in conjunction with the accompanying drawings in which:

30 FIG. 1 is a schematic view showing a keyboard musical instrument according to the present invention;

FIG. 2 is a schematic view showing another keyboard musical instrument according to the present invention;

35 FIG. 3 is a partially cut-away side view showing a pedal mechanism incorporated in yet another keyboard musical instrument according to the present invention; and

FIG. 4 is a front view showing the pedal mechanism.

**DESCRIPTION OF THE PREFERRED
EMBODIMENTS**

40 **First Embodiment**

45 Referring first to FIG. 1 of the drawings, a keyboard musical instrument embodying the present invention largely comprises an upright piano 10, an electronic sound generating system 11, a load applying system 12 and a change-over mechanism 13. In the following description, the term "front" indicates a position closer to a player sitting in front of the upright piano and the term "rear" indicates a position further from the player; a lateral direction is a direction perpendicular to an axis between the front and the rear.

50 The upright piano 10 is a standard upright piano, and includes a piano case 10a and a keyboard 10b mounted on a key bed 10c forming a part of the piano case 10a. A plurality of black keys 10d and a plurality of white keys 10e are arranged in the lateral direction, and form in combination the keyboard 10b. A balance rail 10f extends on the key bed 10c in the lateral direction, and balance pins 10g project from the balance rail 10f at intervals. The black/white keys 10d/10e are turnable around the balance pins 10g, and are maintained at rest positions without any force exerted thereon. A player depresses the front end portions of the black/white keys 10d/10e, and the depressed black/white keys 10d/10e is moved from the rest position to an end position where the lower end surface of the depressed key is brought into contact with a front pin cloth on a front rail (not shown).

The upright piano **10** further includes a plurality of key action mechanisms **10h** respectively linked with the black/white keys **10d/10e**, a plurality of hammers **10i** respectively driven for rotation by the key action mechanisms **10h**, a plurality of sets of strings **10j** respectively struck by the hammers **10i** and a plurality of damper mechanisms (not shown) for damping the strings **10j**. These mechanisms are well known to a skilled person, and description is hereinbelow made on parts for imparting the piano key touch only.

A capstan button **10k** projects from each of the black/white keys **10d/10e**, and is held in contact with a whipped assembly **10m**. The whipped assembly **10m** is turnable around a pin **10n**, and a jack **10o** is turnably supported by the whipped assembly **10m**. A regulating button **10p** is opposed to a toe of the jack **10o**, and the hammer **10i** is engaged with the jack **10o**. While the associated black/white key **10d/10e** is being moved from the rest position to an intermediate position, the capstan button **10k** causes the whipped assembly **10m** to turn in the counter clockwise direction, and the toe of the jack **10o** is getting closer and closer to the regulating button **10p**. The hammer **10i** is rotated toward the set of strings **10j** at low speed. When the toe of the jack **10o** is brought into contact with the regulating button **10p**, the jack **10o** quickly turns on the whipped assembly **10m**, and the hammer **10i** escapes from the jack **10o** so as to start a free rotation. The hammer **10i** strikes the set of strings **10j**, and rebound thereon.

While the black/white key **10d/10e** is traveling from the rest position to the intermediate position where the hammer **10i** escapes from the jack **10o**, the key action mechanism **10h** and the hammer **10i** build up resistance to the black/white key **10d/10e**, and the player feels the key heavy. However, after the escape of the hammer **10i**, the load is decreased, and the player feels the black/white key **10d/10e** lighter. Thus, the key action mechanisms **10h** and the hammers **10i** generate the piano key touch, and as a whole constitute a first key touch generator.

The electronic sound generating system **11** includes a plurality of key sensors **11a** respectively monitoring the black/white keys **10d/10e** for producing key position signals **KP1**, a controller **11b** for processing pieces of positional information represented by the key position signals **KP1** for producing an audio signal **AD** and a head-phone **11c** for producing an electronic sound from the audio signal **AD**. The controller **11b** has a digital signal processor and a tone generator, and produces the audio signal as similar to the prior art electronic keyboard. The controller **11b** allows a user to select one of timbres, and imparts the selected timbre to the electronic sounds.

The load applying system **12** is implemented by a plurality of leaf spring members **12a**. The leaf spring members **12a** are attached to the change-over mechanism **13**. When a player wants a key touch like an electronic keyboard, the leaf spring members **12a** are pressed against the rear upper surfaces of the black/white keys **10d/10e**, respectively, and urge the black/white keys **10d/10e** to return to the respective rest positions. For this reason, when a player depresses a black/white key **10d/10e**, the black/white key **10d/10e** needs to deform the leaf spring member **12a**, and the resistance is substantially constant during the key motion. Thus, the leaf spring members **12a** provides the resistance different from that of the key action mechanisms **10h** and the hammers **10i**, and serve as a second key touch generator.

The change-over mechanism **13** includes an L-letter shaped lifting lever **13a** turnable around a shaft member **13b**, a solenoid-operated actuator unit **13c** having a plunger **13d**

projectable from and retractable into a space defined by a solenoid coil (not shown) and a connecting rod **13e** provided between the plunger **13d** and the L-letter shaped lifting lever **13a**. The L-shaped lifting lever **13a** has a short arm **13f** and a long arm **13g**, and a cushion member **13h** and the leaf spring member **12a** are attached to the short arm **13f** and the long arm **13g**, respectively. Though not shown in the drawings, a coil spring urges the plunger **13d** in a direction projecting from the solenoid coil. When the solenoid-coil is energized, the electro-magnetic force retracts the plunger **13d** into the space.

The change-over mechanism **13** is changed between a first position and a second position. The change-over mechanism **13** is shown in FIG. 6 staying in the first position where the capstan button **10k** is held in contact with the whipped assembly **10m** and the leaf spring members **12a** are spaced from the rear upper surfaces of the black/white keys **10d/10e**. For this reason, the load applying system **12** is disabled, and no resilient force is applied to the black/white keys **10d/10e**. In this situation, when a player depresses a black/white key **10d/10e**, the key action mechanism **10h** and the hammer **10i** causes the player to feel the piano key touch.

When the solenoid coil is energized, the plunger **13d** is retracted, and the L-letter shaped lifting lever **13a** turns in the clockwise direction. The short arm **13f** causes the whipped assembly **10m** to turn in the counter clockwise direction, and the whipped assembly **10m** is spaced from the capstan button **10k**. As a result, the key action mechanism **10h** stands idle during the motion of the black/white key **10d/10e**. On the other hand, the long arm **13g** presses the leaf-spring members **12a** against the rear upper surfaces of the black/white keys **10d/10e**. In this situation, when a player depresses a black/white key **10d/10e**, the black/white key **10d/10e** is moved against the resilient force of the leaf spring member **12a**, and the player feels the key touch like the electronic keyboard. The hammer does not strike the set of strings **10j**, and no acoustic sound is generated. However, the controller **11b** is powered together with the solenoid-operated actuator unit **13c**, and cooperates with the key sensors **11a** so as to generate the electronic sounds. The resistance due to the leaf spring members **12a** is lighter than that of the key action mechanisms/hammers **10h/10i**, and the player can easily perform a fast passage.

Assuming now that a player requests the keyboard musical instrument to generate the acoustic sounds, the solenoid-operated actuator unit **13c** is deenergized, and the plunger **13d** projects so as to change the L-letter shaped lifting lever **13a** from the second position to the first position. The leaf spring members **12a** are spaced from the rear upper surfaces of the black/white keys **10d/10e**, and the whipped assemblies **10m** are brought into contact with the capstan buttons **10k**, respectively. The electric power is not supplied to the controller **11b**.

The player selectively depresses the black/white keys **10d/10e**, and the depressed black/white keys **10d/10e** activate the associated key action mechanisms **10h** so as to strike the sets of strings **10j** with the hammers **10i**. The strings **10j** vibrate, and produce the acoustic sounds. The key action mechanisms **10h** changes the load exerted on the depressed black/white keys **10d/10e** at the escape form the jacks **10o**, and the player feels the key touch like a standard upright piano.

On the other hand, when the player energizes the solenoid-operated actuator unit **13c** and the controller **11b**, the change-over mechanism **13** is changed from the first position to the second position. The whipped assemblies **10h**

are spaced from the capstan buttons **10k**, and the leaf spring members **12a** are pressed against the rear upper surfaces of the black/white keys **10d/10e**. While the player is fingering on the keyboard **10b**, the depressed black/white keys **10d/10e** are moved against the resilient forces of the leaf spring members **12a**, and the player feels the key touch like the electronic keyboard. The key sensors **11a** report the key motions to the controller **11b**, and the controller **11b** produces the audio signal **AD**. The audio signal **AD** is supplied to the head-phone **11c**, and produces the electronic sounds corresponding to the depressed keys.

As will be appreciated from the foregoing description, the change-over mechanism **13** selectively enables the load applying system **12** and the key action mechanisms/hammers **10h/10i**, and the player changes the key touch between the upright piano and the electronic keyboard.

Second Embodiment

Turning to FIG. 2 of the drawings, another keyboard musical instrument embodying the present invention also largely comprises an upright piano **20**, an electronic sound generating system **21**, a load applying system **22** and a change-over system **23**. The upright piano **20** is similar to the upright piano **10**, and the corresponding parts of the upright piano **20** are labeled with the same referenced legends without detailed description.

The electronic sound generating system **21** is also similar to the electronic sound generating system **11**. For this reason, corresponding components of the electronic sound generating system are labeled with the same referenced legends.

The load applying system **22** includes first spring members **22c** urging the black/white keys **10d/10e** toward the rest positions and second spring members **22d** urging the black/white keys **10d/10e** toward the end positions, and the resilient force of each first spring member **22c** is balanced with the resilient force of the associated second spring member **22d** at the rest position of the associated black/white key **10d/10e**.

The load applying system **22** further includes the solenoid-operated actuators **22b**, the position sensors **11a**, a touch selector for selecting one of timbres, a memory **22f** for storing a plurality of key touch tables and a driving circuit for controlling the solenoid-operated actuators **22b**. In this instance, the position sensors **11a** are implemented by photo-interrupters.

Though not shown in the drawings, coil springs retract the plungers **22a** into the yoke **22h**, and the plungers **22a** are held in contact with the rear upper surfaces of the black/white keys **10d/10e**, respectively. When the solenoid coils are energized, the plungers **22a** project from the yoke **22h** against the resilient forces of the coil springs, and pushes down the rear upper surfaces of the black/white keys **10d/10e**. The projecting length of the plunger **22a** is changeable by controlling the amount of electric power supplied to the solenoid coil.

The plurality of key touch tables correspond to the timbres selectable by the player, and a variation of load exerted on the black/white key **10d/10e** is memorized in each of the key touch tables. If the selected timbre is a piano sound, the load is suddenly changed at the escape point, and the key touch table corresponding to the piano sound stores the variation of the load suddenly changed at the escaping point. The load data representative of the variation is sequentially read out from the selected key touch table depending upon the current key position represented by a

key position signal **KP2**, and the driving circuit **22g** changes the magnitude of a driving current signal **DS1**. As a result, the solenoid-operated actuator **22** varies the load with the magnitude of the driving current signal **DS2**, and the player feels the variation of load as a key touch.

The change-over system **23** includes a lifting lever **23a** turnable around a shaft member **23b**, a cushion member **23c** attached to the leading end portion of the lifting lever **23a**, a solenoid-operated actuator unit **23d** having a plunger **23e** connected to the lifting lever **23a** and a controller **23f** for supplying a driving current signal **DS2** and enable signals **EBL1/EBL2**. The cushion member **23a** is held in contact with the whipped assemblies **10m**. A coil spring urges the plunger **23e** of the solenoid-operated actuator unit **23d** to project from the case, and the lifting lever **23a** and the cushion member **23c** allows the whipped assemblies **10m** to be held in contact with the capstan buttons **10k**. However, when the controller **23f** energizes the solenoid-operated actuator unit **23d** with the driving current signal **DS2**, the plunger **23e** is retracted so as to space the whipped assemblies **10m** from the capstan buttons **10k**. In this situation, a depressed black/white key **10d/10e** does not actuate the associated key action mechanism **10h**, and the hammer **10i** is continuously engaged with the jack **10o**.

The controller **23f** further supplies the enable signals **EBL1/EBL2** to the controller **11b** and the memory **22f**. The controller **11b** becomes responsive to the key position signals **KP2** so as to generate the audio signal **AD**, and the load data are sequentially read out from the selected key touch table in response to the key position signals **KP2**.

Assuming now that a player requests the keyboard musical instrument to generate the acoustic sounds, the solenoid-operated actuator unit **23d** is deenergized, and the plunger **23e** projects so as to engage the whipped assemblies **10m** with the capstan buttons **10k**. The enable signals **EBL1/EBL2** are not supplied to the controller **11b** and the memory **22f**, and they are disabled.

The player selectively depresses the black/white keys **10d/10e**, and the depressed black/white keys **10d/10e** actuate the associated key action mechanisms **10h** so as to strike the sets of strings **10j** with the hammers **10i**. The strings **10j** vibrate, and produce the acoustic sounds. The key action mechanisms **10h** changes the load exerted on the depressed black/white keys **10d/10e** at the escape form the jacks **10o**, and the player feels the key touch like a standard upright piano. The plungers **22a** are retracted into the cases, and no load is applied to the black/white keys **10d/10e**.

On the other hand, when the player requests the keyboard musical instrument to generate the electronic sounds, the controller **23f** supplies the driving current signal **DS2** to the solenoid-operated actuator unit **23d**, and the solenoid-operated actuator unit **23d** retracts the plunger **23e** into the case. As a result, the lifting lever **23a** causes the whipped assemblies **10m** to turn in the counter clockwise direction, and the whipped assemblies **10m** are spaced from the capstan buttons **10k**.

The controller **23f** supplies the enable signals **EBL1/EBL2** to the controller **11b** and the memory **22f**, and the electronic sound generating system **21** and the load applying system **22** are activated. The player may select a timbre through the manipulation of the touch selector **22e**.

The white key **10e** is assumed to be depressed during the performance. The white key **10e** is traveling from the rest position toward the end position. The position sensor **11a** is detecting the current key position, and supplies the key position signal **KP2** representative of the current key posi-

tion. The controller 11b produces a music data code on the basis of the key position signal KP2, and tailors the audio signal AD from the music data code. An appropriate envelope is applied for the selected timbre, and an electronic sound is generated through the head-phone 11c.

While the position sensor 11a is varying the value of the key position signal KP2, the load data are sequentially read out from the key touch table corresponding to the selected timbre, and are supplied to the driving circuit 22g. The driving circuit 22g is responsive to the load data, and changes the magnitude of the driving current signal DS1 with the load data. The solenoid operated actuator unit 22b changes the electromagnetic force in proportional to the magnitude of the driving current signal DS1 or the load data, and the player feels the load exerted on the white key 10e as a key touch like the keyboard musical instrument for which the timbre is selected.

If the player wants to finger on the keyboard 10b in an extremely light key touch, the controller 23f supplies the driving current signal DS2 and the enable signal EBL2 to the solenoid-operated actuator unit 23d and the controller 11b only. In this situation, only the electronic sound generating system 21 is enabled, and the first and second springs 22c/22d generate the extremely light key touch.

As will be understood from the foregoing description, the change-over system 23 changes the key touch between the upright piano and other keyboard musical instrument such as an electronic keyboard, harpsichord and a celesta.

Third Embodiment

Turning to FIGS. 3 and 4 of the drawings, a pedal mechanism 20 is incorporated in yet another keyboard musical instrument embodying the present invention. Although the keyboard musical instrument further includes a keyboard, an electronic sound generating system, a load applying system and a change-over mechanism, these are similar to those of the first embodiment or the second embodiment, and are not detailed hereinbelow.

The pedal mechanism 20 includes a pedal 20a turnable around a shaft member 20b and a pedal shaft 20c connected to the pedal 20a, and the pedal shaft 20c is slidably supported by a frame 21a of the upright piano so that the pedal 20a moves the pedal shaft 20c in an up-and-down direction.

The pedal mechanism 20 further includes a pedal arm 20d turnable around a shaft member 20e, and is shaped into an L-letter configuration. The pedal shaft 20c is held in contact with one end portion of the pedal arm 20d, and causes the pedal arm 20d to turn around the shaft member 20e. Damper mechanisms 21b are engaged with the pedal arm 20d, and are spaced from the sets of strings by the pedal arm 20d. When a player depresses the pedal 20a, the damper shaft 20c is upwardly lifted, and the damper arm 20d turns around the shaft member 20e so as to space the dampers of the damper mechanisms 21b from the sets of strings. Thus, the player feels the load due to the damper mechanisms 21b. When the keyboard musical instrument implementing the third embodiment serves as an acoustic upright piano, the pedal mechanism 20 behaves as similar to the damper pedal mechanism of a standard upright piano. However, when the keyboard musical instrument serves as an electronic keyboard, another change-over mechanism 23 disables the damper mechanisms 21b, and another load applying mechanism 24 exerts load on the pedal 20a.

The change-over mechanism 23 includes a toggle 23a turnable around a shaft member 23b, a solenoid-operated actuator unit 23c having a plunger 23d, a connecting rod 23e

connected between the plunger 23d and the toggle 23a and a spring member 23f urging the plunger 23d into the case of the actuator unit 23c. The solenoid-operated actuator unit 23c is stationary with respect to a piano case, and the shaft member 23b is stationary with respect to an angle member 23g attached to the piano case. A roller 23h of the toggle 23a is held in contact with the pedal arm 20d.

While no current is supplied to the solenoid-operated actuator unit 23c, the spring member 23f retracts the plunger 23e into the case, and the connecting rod 23e causes the toggle 23a to decline from the vertical position. As a result, the toggle 23a allows the pedal arm 20d to be held in contact with the pedal shaft 20c, and the pedal arm 20d transfers the motion of the pedal shaft 20c to the damper mechanisms 21b. On the other hand, when the solenoid-operated actuator unit 23c is energized, the plunger 23d projects from the case, and changes the toggle 23a to the vertical position. The roller 23h lifts the pedal arm 20d, and spaces the pedal arm 20d from the pedal shaft 20c. For this reason, Even if a player depresses the pedal 20a, the pedal shaft 20c does not push the pedal arm 20d. Thus, the change-over mechanism 23 changes the damper mechanisms 21b between the disable state and the enable state.

The load applying system 24 includes a solenoid-operated actuator unit 24a having a plunger 24b fixed to the pedal shaft 20c, a pedal sensor 24c monitoring the pedal shaft 20c and, accordingly, the pedal 20a, a touch selector 24c, a memory 24d and a driving circuit 24e. The pedal sensor 24c produces a pedal position signal PS indicative of current pedal position, and supplies the pedal position signal PS to both of the controller 25a of the electronic sound generating system and the memory 24d. The controller 25a is responsive to the pedal position signal PS, and prolongs the electronic sound as similar to the lifted dampers prolong the acoustic piano sounds. In this instance, the pedal sensor 24c is implemented by photo-interrupters.

The yoke unit 24f of the solenoid-operated actuator unit 24a is fixed to the piano case, and a solenoid-coil 24g is accommodated in the yoke unit 24f. The plunger 24b is movable together with the pedal shaft 20c. When the solenoid coil 24g is energized, the solenoid coil 24g generates electromagnetic force, and downwardly urges the plunger 24b and, accordingly, the pedal shaft 20c. A player feels the electromagnetic force as a load exerted on the pedal 20a. The load is variable with the current pedal position as described hereinbefore.

A plurality of pedal touch tables are stored in the memory 24d, and each of the pedal touch tables contains a series of load data variable with the current pedal position. The sets of load data are representative of variations of the load exerted on the pedal 20a of different keyboard musical instruments. A player selects one of the pedal touch tables by manipulating the touch selector 24c.

When a player selects one of the pedal touch tables, the load data are sequentially read out from the selected pedal touch table to the driving circuit 24e in dependence on the current pedal position, and the driving circuit 24e generates a driving current signal DS3 on the basis of the load data. The magnitude of the driving current signal DS3 varies together with the magnitude of the load, and the driving signal DS3 is supplied to the solenoid-operated actuator unit 24a. The solenoid-operated actuator unit 24a generates the electromagnetic force from the driving current signal DS3, and the player feels the load on the pedal 20a as if the damper mechanisms 21b exerts the weight on the pedal 20a.

Assuming now that a player requests the keyboard musical instrument to serve as the upright piano, the change-over

mechanism 23 allows the pedal arm 20d to be held in contact with the pedal shaft 20c, and the player lifts the dampers of the damper mechanisms 21b by depressing the pedal 20a. The player feels the standard pedal touch of the damper pedal.

On the other hand, when the player requests the keyboard musical instrument to serve as an electronic keyboard, the solenoid-operated actuator unit 23c is energized, and the plunger 23d projects from the case. The toggle 23a is changed to the vertical position, and spaces the pedal arm 20d from the pedal shaft 20c. The touch selector 24c specifies the pedal touch table representative of the variation of load for the electronic keyboard.

While the player is playing a tune on the keyboard, the electronic sound generating system produces the electronic sounds instead of the piano sounds, and the load applying system exerts load to the black/white keys as described in conjunction with the first and second embodiments.

The player is assumed to depress the pedal 20a during the performance, and the pedal 20a upwardly lifts the pedal shaft 20c. The motion of the pedal shaft 20c is detected by the pedal sensor 24c, and the current pedal position is transferred to the controller 25a and the memory 24d by the pedal position signal PS. The controller 25a imparts the effect similar to the damper pedal to the electronic sounds.

The load data are sequentially read out from the selected table to the driving circuit 24e, and the driving circuit 24e changes the magnitude of the driving current signal DS3 depending upon the load data. The solenoid-operated actuator unit 24a exerts the load on the pedal 20a through the pedal shaft 20c, and the load varies like the load on the pedal of the electronic keyboard. For this reason, the player feels the pedal touch like the pedal of the electronic keyboard.

The keyboard musical instrument implementing the third embodiment achieves all the advantages of the second embodiment and an additional advantage in the pedal touch like that of selected keyboard musical instrument.

In this instance, the damper mechanisms serve as a first pedal touch generator, and the solenoid-operated actuator unit 24a, the pedal sensor 24c, the memory 24d and the driving circuit 24e as a whole constitute a second pedal touch generator.

As will be appreciated from the foregoing description, the load applying system and the change-over system give different touch to the player, and a player uses the keyboard musical instrument according to the present invention as different kinds of keyboard musical instruments.

Although particular embodiments of the present invention have been shown and described, it will be obvious to those skilled in the art that various changes and modifications may be made without departing from the spirit and scope of the present invention.

For example, the solenoid-operated actuators 22b may be placed under the front portions of the black/white keys 10d/10e as indicated by dots-and-dash line in FIG. 2. In this instance, the position sensors 11a may monitor the plungers of the solenoid-operated actuators 22b.

A keyboard musical instrument may have the change-over mechanism 23 and the load applying system 24 only.

Moreover, a key/pedal sensor may detect a key/pedal velocity, a key/pedal acceleration or a force exerted on the key/pedal.

What is claimed is:

1. A keyboard musical instrument comprising:

a keyboard having a plurality of keys movable between rest positions and end positions when fingers of a player selectively depress said plurality of keys;

a sound generating system responsive to a motion of each of said plurality of keys so as to generate a sound; a first key touch generator connectable to said plurality of keys, and providing a first resistance against said fingers through keys depressed by said player;

a second key touch generator connectable to said plurality of keys, and providing a second resistance different from said first resistance against said fingers through the keys selectively depressed by said player; and

a change-over unit connected to said first key touch generator and said second key touch generator, and responsive to an instruction of said player for selectively connecting said first key touch generator and said second key touch generator to said plurality of keys.

2. The keyboard musical instrument as set forth in claim 1, in which said sound generating system includes a plurality of strings vibrating for producing a first kind of said sound and an electronic sound generating system for generating a second kind of said sound, and

said first key touch generator includes a plurality of key action mechanisms linked with said plurality of keys and a plurality of hammers escaping from said plurality of key action mechanisms on the way from said rest positions and said end positions for striking said plurality of strings.

3. The keyboard musical instrument as set forth in claim 2, in which each of said plurality of key action mechanisms has a capstan button projecting from one of said plurality of keys and a whipped assembly held in contact with said capstan button so that said whipped assembly turns during a motion of said one of said plurality of keys, and

said change-over unit causes said whipped assembly to forcibly turn so as to space said whipped assembly from said capstan button when said change-over unit actuates said second key touch generator.

4. The keyboard musical instrument as set forth in claim 1, in which said sound generating system includes a plurality of strings vibrating for producing a first kind of said sound and an electronic sound generating system for generating a second kind of said sound,

said first key touch generator includes a plurality of key action mechanisms linked with said plurality of keys and a plurality of hammers escaping from said plurality of key action mechanisms on the way from said rest positions and said end positions for striking said plurality of strings, and

said second key touch generator includes a plurality of spring members attached to said change-over unit and urging said plurality of keys toward said rest positions, respectively.

5. The keyboard musical instrument as set forth in claim 4, in which each of said plurality of key action mechanisms has a capstan button projecting from one of said plurality of keys and a whipped assembly held in contact with said capstan button so that said whipped assembly turns during a motion of said one of said plurality of keys, and

said change-over unit causes said whipped assembly to forcibly turn so as to space said whipped assembly from said capstan button and said plurality of spring members to urge said plurality of keys when said second key touch generator is selected to be actuated, said change-over unit causing said whipped assembly to be in contact with said capstan button and spacing said plurality of spring members from said plurality of keys when said first key touch generator is selected to be actuated.

11

6. The keyboard musical instrument as set forth in claim 1, in which said sound generating system includes a plurality of strings vibrating for producing a first kind of said sound and an electronic sound generating system for generating a second kind of said sound,

said first key touch generator includes a plurality of key action mechanisms linked with said plurality of keys and a plurality of hammers escaping from said plurality of key action mechanisms on the way from said rest positions and said end positions for striking said plurality of strings, and

said second key touch generator includes

a memory having at least one key touch table for storing a series of load data representative of a load to be exerted on said plurality of keys for producing said second resistance,

a driving circuit responsive to said series of load data read out from said at least one key touch table depending upon a current key position of one of said plurality of keys moved from said rest position to said end position and producing a driving current signal changed with said current key position, and a solenoid-operated actuator having a solenoid supplied with said driving current signal and a plunger movable with respect to said solenoid so as to impede the motion of said one of said plurality of keys.

7. The keyboard musical instrument as set forth in claim 6, in which each of said plurality of key action mechanisms has a capstan button projecting from one of said plurality of keys and a whipped assembly held in contact with said capstan button so that said whipped assembly turns during a motion of said one of said plurality of keys, and

said change-over unit causes said whipped assembly to forcibly turn so as to space said whipped assembly from said capstan button and said memory and said driving circuit to respond to said current key position when said second key touch generator is selected to be actuated,

said change-over unit causing said whipped assembly to be in contact with said capstan button and disabling said memory and said driving circuit when said first key touch generator is selected to be actuated.

8. The keyboard musical instrument as set forth in claim 6, in which said at least one key touch table is divided into

12

a plurality of key touch sub-tables different in said series of load data from one another, and a player selects one of said plurality of key touch sub-tables.

9. The keyboard musical instrument as set forth in claim 1, further comprising

at least one pedal for giving a musical effect to said sound, said sound generating system responsive to said at least one pedal for giving said musical effect to said sound; a first pedal touch generator connected to said at least one pedal, and responsive to a motion of said at least one pedal for providing a third resistance to a motion of said at least one pedal;

a second pedal touch generator connected to said at least one pedal, and responsive to said motion of said at least one pedal for providing a fourth resistance different from said third resistance to said motion of said at least one pedal; and

another change-over unit connected to said first pedal touch generator and said second pedal touch generator, and selectively enabling said first pedal touch generator and said second pedal touch generator.

10. A keyboard musical instrument comprising:

a keyboard for specifying a note of a scale; a sound generating system responsive to a motion of said keyboard for generating a sound;

at least one pedal for giving a musical effect to said sound; a first pedal touch generator connectable to said at least one pedal, and responsive to a motion of said at least one pedal for providing a first resistance against said foot through said at least one pedal;

a second pedal touch generator connectable to said at least one pedal, and responsive to said motion of said at least one pedal for providing a second resistance different from said first resistance against said foot through said at least one pedal; and

a change-over unit connected to said first pedal touch generator and said second pedal touch generator, and responsive to an instruction of said player for selectively connecting said first pedal touch generator and said second pedal touch generator to said at least one pedal.
